UNITED STATES PATENT OFFICE.

JAMES H. SAGER, OF ROCHESTER, NEW YORK.

SHOCK-ABSORBER.

973,217.

Specification of Letters Patent. Patented Oct. 18, 1910.

Application filed May 3, 1910. Serial No. 559,238.

To all whom it may concern:

Be it known that I, JAMES H. SAGER, a citizen of the United States, and resident of Rochester, in the county of Monroe and

5 State of New York, have invented certain new and useful Improvements in Shock-Abso-
rbers, of which the following is a specifi-
cation.

This invention relates particularly to
10 shock-absorbers for bicycles, and the object
of the invention is to produce a bicycle-
frame provided with a shock-absorbing de-
vice, this frame being of simple, compact
and inexpensive construction.

15 Another object of the invention is to pro-
vide the frame with a novel and improved
pivotal connection between the rear fork
and the crank-hanger, to permit the yield-
ing movements of the rear fork necessary
20 in connection with the shock-absorber. To
these ends the invention consists in the novel
construction hereinafter described, as it is
defined in the succeeding claims.

In the drawings: Figure 1 is a side eleva-
25 tion of a portion of a bicycle-frame in which
the present invention is embodied, the upper
portion of the frame being shown in section
to illustrate the construction of the shock-
absorber, and the crank-hanger and asso-
30 ciated parts being shown in section on the
line 1—1 in Fig. 3, looking from left to
right in said figure; Fig. 2 is a vertical sec-
tion, on an enlarged scale, on the line 2—2
in Fig. 1, looking from right to left in said
35 figure; Fig. 3 is a rear elevation of the
crank-hanger and associated parts; Fig. 4 is
a section, on an enlarged scale, on the line
4—4 in Fig. 1, looking from right to left
in said figure and Fig. 5 is a side elevation,
40 showing in detail the connection between the
rear stays and the slide.

The invention is illustrated as embodied
in a bicycle-frame of the usual diamond-
shape. The slide is in the form of a cy-
45 lindrical member 5 which is inclosed and
guided within the horizontal upper frame-
tube 6. The rear stays 7 of the frame are
connected with the slide by means of a pin
8, which passes loosely through the slide
50 and through the upper ends of the stays and
is provided at its ends with lock-nuts 9 by
which the parts are adjusted closely but
loosely together so as to permit relative
pivotal movements of the slide and the stays.
55 The pin 8 passes through horizontal slots
10 in the tube 6 to permit the slide to move

longitudinally in the tube, and washers 11
are interposed between the stays and the
slide to prevent contact between the stays
and the tube 6.

60 The movements of the slide and the stays
are controlled by a compression spring 12
which is inclosed within the tube 6. The
forward end of the spring rests against a
plug 13 fixed in the tube, while the rear 65
end of the spring engages the slide. In
order to produce a slide of slight weight but
with a long bearing surface, the slide is re-
cessed in front, as shown in Fig. 1, and a
portion of the spring is received in the re-
70 cess. To cushion rebounding movement of
the slide a second spring 14 is placed behind
the slide, in the tube 6, and the saddle-post
15 serves as an abutment for the rear end
of this spring.

75 The rear stays 7 are pivoted at 8 to the
rear ends of the rear fork 9 in the usual
manner, and the rear fork is also pivoted
to the crank-hanger in a manner presently
to be described. These pivotal connections, 80
together with the movable slide, permit ver-
tical yielding movements of the rear wheel
when irregularities in the road surface are
encountered, and in this respect the opera-
tion of the device is substantially similar to 85
that of previous forms of cushion frames
for bicycles. In the present construction,
however, the arrangement of the slide and
the rear stays provides for a novel fric-
tional action, while the employment of the 90
horizontal frame-tube to inclose the slide
and the springs results in a very simple and
compact construction. This construction is
particularly adapted for use in motor-
cycles, where it is desirable to make the 95
frame as low as possible, since in the pres-
ent construction the shock-absorbing ele-
ments are located entirely in front of the
mast-tube 16 of the frame.

100 The pivotal connection between the rear
fork and the crank-hanger is illustrated
particularly in Figs. 2 and 3. The side
members of the rear fork are rigidly con-
nected, at their forward ends, with a sleeve
17 which contains the ball-bearings 18 upon
105 which the crank-shaft 19 is journaled. The
sleeve 17 is journaled within the crank-
hanger 20 of the frame, this crank-hanger
being of the usual cylindrical form and
being connected in the usual manner with 110
the mast-tube 16 and the forward inclined
tube 21 of the frame. To permit the intro-

duction of the sleeve 17 in the crank-hanger the latter is slotted at the rear, from its right-hand end, as shown in Fig. 3, so that the sleeve may be introduced through this 5 end, the rear-fork members entering the slot as in Fig. 3. The slot is slightly enlarged above the positions normally occupied by the rear-fork members, to provide for vertical movements of the latter when the 10 device is in operation. To retain the sleeve in the crank-hanger and prevent end motion, the ends of the crank-hanger are threaded to receive threaded cap-rings 22 which overhang the ends of the sleeve, as 15 shown in Fig. 2.

To facilitate assembling the shock-absorber an opening 23 is provided in the rear of the mast-tube 16, in line with the horizontal tube 6. The springs and the slide are introduced through the opening 23, the rear stays 20 are then fastened to the slide by passing the pin 8 through the parts and fixing the nuts 9 in place, the sleeve 17 is then inserted, in the manner above described, in the crank-hanger, and the rear stays are finally connected with the rear fork at the pivotal 25 points 8.

I claim:—

1. In a cushion-frame for bicycles, a pivotal connection between the rear fork and 30 the forward portion of the frame comprising

ing, in combination with the crank-shaft, the crank-hanger and the rear fork, a sleeve in which the crank-shaft is journaled, said sleeve being journaled in the crank-hanger 35 and rigidly connected with the rear fork, and the crank-hanger being slotted at the rear to permit the rear fork and the sleeve to be inserted through the end of the crank-hanger, and means for preventing endwise 40 movement of the sleeve in the crank-hanger.

2. In a cushion-frame for bicycles, the combination of an upper tube, a mast-tube having a rearward opening in line with the upper tube, a saddle-post removably secured 45 in the mast-tube, a slide in the upper tube, rear stays connected at their upper ends with the slide, a spring in the upper tube for controlling forward movement of the slide, and a second spring in the upper tube 50 between the slide and the saddle-post for controlling the rearward movement of the slide, the saddle-post serving normally as an abutment for the latter spring and being removable to permit the insertion of the 55 spring and the slide through said rearward opening of the mast tube.
